(57) **CLAIM**

The ornamental design for a landscape light, as shown and described.

DESCRIPTION

FIG. 1 is a first perspective view of a landscape light showing my new design;

FIG. 2 is a second perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is an enlarged view of the selected portion in FIG. 1; and,

FIG. 10 is an enlarged view of the selected portion in FIG. 1.

The broken lines shown in the drawings depict portions of the landscape light in which the design is embodied that form no part of the claimed design.
